UNITED STATES PATENT OFFICE

ALEXANDER E. BLOCK, OF ST. LOUIS, MISSOURI

FOOT-TREATMENT APPLIANCE

Application filed December 31, 1927. Serial No. 243,787.

My invention relates to improvements in foot-treatment appliances and has for its object the production of an adjustable support for the anterior metatarsal arch of the wearer's foot, together with improvements for adjustably supporting both the inner and the outer longitudinal arch of the wearer's foot, as well as the heel of the wearer.

My invention grows out of the necessity of supporting either or both of the longitudinal arches of the wearer's foot, and one side or the other of the wearer's heel, while treating the various displacements of the bones forming the anterior metatarsal arch. Such cooperative adjustments are not required in all instances, but it is highly desirable to have an appliance which has the capacity for such adjustments in order to adapt itself to the treatment of a wide range of distortions or injuries of the anterior metatarsal arch, as well as either or both of the longitudinal arches, and abnormal conditions of the heel of the wearer's foot.

Furthermore, appliances of this class are to be employed in shoes having various degrees of curvature of the sole, and my appliance provides for the mounting of the appliance within shoes whose soles have varying curvature, and of providing within itself for the adjustment of the various parts with the appliance resulting from such curvature.

Again, an object of my invention is to provide an appliance capable of adjustment before being placed in the shoe, as well as after it has been mounted in the shoe; and capable of entire removal from the shoe when desired. The operation of removal from the shoe may be to replace the adjusted appliance in another shoe, or simply because the treatment of the foot has been successful, and the presence of the appliance within the shoe is no longer necessary.

An additional object of my invention resides in the wide range of adjustability which is attained thereby, and which will be elaborated in the descriptive portion of this specification. From that description will also be made evident the economy of material and workmanship which I have attained by the simple construction of the various parts and

the minimum amount of labor involved in their manufacture.

Drawings

In the drawings, 55
Fig. 1 is a top plan view of an appliance embodying my invention.

Fig. 2 is a bottom plan view of the same. Fig. 3 is a top plan view of the same with the top layer lifted and folded back for the purpose of the insertion of the elements employed in treating the anterior metatarsal arch; the base insole being also lifted to disclose the pocket formation of the rear of the appliance. 60

Fig. 4 is a transverse sectional view taken on the line 4—4 of Fig. 1.

Fig. 5 is a fragmental longitudinal section of the appliance taken on the line 5—5, of Fig. 1. 70

Fig. 6 is a top plan view of one of the bifurcated holders carrying inserts for the treatment of the longitudinal arches and heel of the wearer's foot.

Fig. 7 is a top plan view of one of the inserts intended to be mounted in the holder illustrated in Fig. 6. 75

Fig. 8 is a transverse sectional view of the holder illustrated in Fig. 6, taken on the line 8—8 of Fig. 6.

Fig. 9 is a transverse sectional view of the insert illustrated in Fig. 7.

Fig. 10 is a transverse sectional view of the holder shown in Fig. 6 with two inserts in place, taken on the line 8—8 of Fig. 6. 85

Fig. 11 is a top plan view of the eccentrically-humped insert employed in the treatment of the anterior metatarsal arch, of which Fig. 12 is a sectional view taken on the line 12—12 of Fig. 11, Fig. 13 is a like view taken on the line 13—13 of Fig. 11, and Fig. 14 is a transverse sectional view taken on the line 14—14 of Fig. 11. 90

Fig. 15 is a plan view of the carrier employed in the treatment of the anterior metatarsal arch, indicating two of the inserts shown in Fig. 11 in place. 95

Fig. 16 is an edge view of the carrier shown in Fig. 15 with one of the inserts of Fig. 11 in place. 100

Fig. 17 is a plan view showing the carrier of Fig. 15 in place, with one of the inserts of Fig. 11 mounted on said carrier.

Fig. 18 is a transverse sectional view taken on the line 18—18 of Fig. 17.

Fig. 19 is a view similar to that of Fig. 18, with the eccentrically-humped insert of Fig. 11 in reversed position.

Fig. 20 is a view of the carrier of Fig. 15 in place between the base insole and top layer, taken on the line 18—18 of Fig. 17, and showing in section two of the inserts of Fig. 11 in place upon said carrier.

Fig. 21 is a transverse sectional view taken on the line 21—21 of Fig. 3, and showing one of the holders of Fig. 6 in place, with two of the inserts of Fig. 7 mounted in said holder.

Fig. 22 is also a transverse sectional view taken on the line 21—21 of Fig. 3 showing two of the holders of Fig. 6 in place and two of the inserts of Fig. 7 mounted in each of said holders.

Fig. 23 is also a transverse sectional view taken on the line 21—21 of Fig. 3, showing two of the holders of Fig. 6 in place and one of the inserts of Fig. 7 in place in each of said holders.

Description

I employ a base insole A as the base whereon my appliance is constructed. The co-extensive top layer B has its front end secured to the front end of the insole A by the line 30 of stitching 30. Upon the lower face of the base insole A the flap C is secured by the curved line of stitching 31, to form the left hand pocket 32.

The flap D is mounted beneath the flap C, 40 and is secured to said flap C and (at its forward end) to the base insole A by the line of stitching 33, to form the right hand pocket 34.

Toward its rear end the base insole A is 45 provided with a series of transverse slots 35, each of which slots is capable of receiving the locking tongue 36, which tongue 36 is formed in the top layer B, and is illustrated in section in locked position in Fig. 5.

Slightly forward of its longitudinal center, the base insole A is provided with a series of transverse slots 37 which are arranged to receive the constricted tail 38 of the carrier E, in the manner shown in Fig. 17. 50 The function of the carrier E is to serve as a mount for one or more of the inserts F, said inserts F having an eccentric hump 39. This eccentric hump 39 permits the insert F to afford two different high points of support by being reversed, top for bottom, upon the carrier E. The carrier E is provided with various slots 40 to provide for the adjustment of the insert F forwardly, rearwardly, or widewise, as shown in Fig. 15.

55 The insert F is provided with a series of

marginal slots 41 arranged to lock said insert F in place within either of the slots 40 of the carrier E. The insert F is of the contour shown in Figs. 11, 12, 13, and 14, and the slots 41 are formed in its sides toward its thin and tapering rear terminal 43.

One or two of the inserts F being mounted in the desired position upon the carrier E, the carrier E is laid in place upon the base insole A, with the forward edge 42 of the carrier E in proximity to the line of stitching 30 (see Fig. 17). Thereupon, the top layer B, which has been lifted from the base insole A, as shown in Fig. 3, for the reception of the carrier E, is brought downwardly to cover the carrier E and insert F. As the bulk of the insert E, with its carrier F, when in place, will serve to bring the rear edge of the top layer B forward of the rear edge of the base insole A, the locking tongue 36 will be placed in position within one of the slots 35, as shown in Fig. 5, to secure the top layer B in place and prevent it from slipping under the pressure of the foot of the wearer. As indicated by the stippling shown on the lower face of the top layer B in Fig. 3, I employ a slightly tenuous adhesive upon its entire surface, so that said top layer B may, by moistening the adhesive, be caused to adhere lightly to the opposed top surface of the base insole A, as a further preventative of slipping when in place. Such adhesion is only temporary, and must permit the ready lifting of the layer B when it is desired to alter the adjustment of the insert F upon its carrier E.

Beneath the base insole A are the pockets 32 and 34, each extending from the rear end of the appliance to a point under the longitudinal arches of the wearer's foot, and for use within said pockets 32 and 34 I have provided bifurcated holders G, consisting of a base 50 having the outline shown in Fig. 6, to the inner edge of which is secured the cover 51 by means of the line of stitching 52, thus forming the pocket 53. Upon the bottom surface of the cover 51 is secured a layer 54 having the superficial outline shown in Fig. 6, and secured to the cover 51 by the line of stitching 55, thus forming the pocket 56 (see Fig. 10). The inserts H are of the form shown in Fig. 7 and are contoured to substantially fill the pockets 53 and 56. I have illustrated in Fig. 21 the use of two of the inserts H in one of the holders G. In Fig. 22 I have shown the use of two of the holders G, one in each of the pockets 32 and 34, each of said holders G being provided with two of the inserts H.

By the described structure I am enabled to treat either of the metatarsal joints by means of the various adjustments of the insert F, and to treat either of the longitudinal arches by means of the inserts H. By the use of the inserts H I provide support

for the inner or outer sides of the heel of the wearer in conjunction with the corresponding arch of the foot; and the adjustment of the heel and arch may be regulated in coincidence with the treatment of the anterior metatarsal arch at whatever point or area along the line of the anterior metatarsal arch that may need support.

To removably secure the appliance in place 10 within the shoe, the entire bottom surface of the appliance as indicated in Fig. 2 by stippling, is coated with rubber cement, or like adhesive, so as to be substantially glued in place within the wearer's shoe; but the degree 15 of adhesion must be such as to permit the removal of the appliance when occasion requires it.

Variations of structure may be effected in the construction which I have illustrated and 20 described without departure from my actual invention as defined in the appended claims.

I claim:

1. An improved foot-treatment appliance comprising a base insole and a co-extensive 25 top layer of like material secured together transversely at their front ends; a tongue formed in said top layer; and locking means formed in said base layer for the reception of said tongue at various points in said base 30 layer.

2. A foot-treatment appliance comprising a slotted carrier and an insert adapted to be mounted in either of the slots of said carrier; with a base insole and a co-extensive 35 top layer arranged to receive said carrier between them; and means for adjustably securing said top layer to said base insole.

3. A foot-treatment appliance comprising a slotted carrier and an eccentrically-humped 40 insert adapted to be mounted in either of the slots of said carrier; with a base insole and a co-extensive top layer arranged to receive said carrier between them; and means for adjustably securing said top layer to said base insole.

4. A foot-treatment appliance comprising a base insole contoured to fit the interior of a shoe rearwardly from the line of the anterior metatarsal arch of the wearer; a co-extensive top layer secured at its forward 50 end to said insole; a carrier arranged to be held between said insole and top layer; an insert arranged to be held by said carrier; flaps mounted beneath said base insole and 55 forming a right-hand pocket and a left-hand pocket beneath the longitudinal arch and heel of the wearer; bifurcated holders contoured to fit said pockets; and inserts contoured to fit said bifurcated holders.

5. A foot-treatment appliance comprising a slotted carrier and a slotted insert adapted to be mounted in either of the slots of said carrier; with a base insole and a co-extensive top layer arranged to receive said 65 carrier between them; and means for adjust-

ably securing said top layer to said base insole.

6. In a foot-treatment appliance a slotted carrier and a slotted insert arranged to be adjustably mounted in either of the slots in 70 said carrier.

In testimony whereof I have hereunto affixed my signature.

ALEXANDER E. BLOCK.
